JACK FOR KNITTING MACHINE NEEDLES

Edmond O. Roy, Franklin, N. H., assignor to
 Franklin Needle Company, Franklin, N. H., a
 corporation of New Hampshire

Application May 12, 1934, Serial No. 725,325

1 Claim. (Cl. 66—124)

This invention relates to needle jacks such as are employed in certain types of knitting machines for manipulating the needles, and especially to that type of needle jack which is formed 5 with a shallow recess in one side, in which recess is located a resilient leaf spring that resiliently and frictionally engages the wall of the groove in the knitting machine in which the jack slides so that sufficient friction will be produced 10 to hold effectively the jack and its needle from movement in the groove at such times as the jack is not under the control of the operating cam or cams, thereby preventing the jack and its needle from being accidentally displaced by 15 reason of vibration of the machine or from any other cause.

A jack of this type can be advantageously used in various types of knitting machines. In the case of a flat link and link type of knitting machine having a racking mechanism a jack embodying this invention is useful in holding the jack and its needle in retracted position during the racking of the knitting machine.

In some respects the invention is an improvement 25 on the jack shown in Patent No. 1,940,520, December 19, 1933. The features wherein the invention resides will be more fully hereinafter set forth and then pointed out in the appended claim.

In the drawing, 30 Fig. 1 is a fragmentary sectional view of a knitting machine employing my improved jack;

Fig. 2 is a side view of the jack;

Fig. 3 is an enlarged section on the line 3—3, 35 Fig. 2;

Fig. 4 is a perspective view of the leaf spring;

Fig. 5 is an enlarged section on the line 5—5, 30 Fig. 2;

Fig. 6 is a fragmentary perspective view of the jack before the leaf spring has been attached.

Inasmuch as the invention relates simply to the jack for the knitting machine I have not thought it necessary to illustrate in detail any part of the machine other than the portion thereof of having the grooves in which the jacks and 45 needles operate.

In the drawing 1 indicates the portion of a knitting machine in which the jacks and needles operate and which may be a needle plate of a flat type machine or the cylinder of a circular machine or the corresponding part of any other knitting machine. Such portion of the knitting machine, which for convenience will be referred to as the needle-receiving portion, is provided with the usual grooves 2 in which the jacks and 55 needles operate.

4 indicates one of the needle jacks, this being provided with the usual butt or lateral extension 5 which has engagement with the cam mechanism by which the needles are actuated, such jack being formed with the recess 6 at its forward end for the purpose of operatively engaging a needle indicated at 7.

As stated above the jack embodying this invention is of that type which is provided with a shallow recess 8 in one side, in which recess is 10 received a leaf spring 9 that projects slightly beyond the surface of the jack and has a resilient frictional engagement with the wall 10 of the groove 2.

In making the jack embodying this invention the latter is formed with the recess 8 in any suitable way as by means of a die, and in forming the recess 8 one end 11 thereof is made slightly deeper than the remaining portion of the recess. The jack is also formed with a spring-retaining 20 projection 12 rising from the bottom of the recess, said projection preferably being integral with the jack. If the recess is made by means of a die or by the metal stamping operation, then the die will be provided with a recess corresponding to the shape of the projection 12 so that when the jack is placed in the press and is subjected to the action of the die for forming the recess 8 the projection 12 will be formed.

The spring 9, which is a slightly bowed leaf 30 spring, is formed with an opening 13 of a size to receive the projection 12.

In attaching the spring to the jack the spring will be placed in the recess with the opening 13 thereof registering with the projection 12 so that 35 said projection will extend through the opening 13. This projection is then headed over as shown at 14 sufficiently to retain the spring in the recess.

The spring has a thickness slightly less than the depth of the recess so that when the spring 40 is in the recess the outer face of the ends of the spring will be below the side surface of the jack, the center bowed portion of the spring, of course, projecting slightly beyond the side of the jack. 45

The operation of heading over the projection 12 reduces the length of the projection slightly and when this heading-over operation is completed the end surface 15 of the projection will preferably be slightly below the side face of the jack. 50 When the jack is in the groove 2 the bowed portion of the spring which extends beyond the jack will have sufficient resilient frictional engagement with the wall 10 of the groove to hold the jack and its needle from being displaced in the 55

groove at such time as the jack is not under the control of a cam.

The forming of the recess and the attaching of the spring to the jack in the manner above described can be accomplished without in any way distorting the jack or producing any irregularities in its surface which will interfere with its smooth and correct operation in the knitting machine.

10 The construction shown also provides a practical and effective way of anchoring the spring in the recess of the jack.

The purpose of making the recess slightly deeper at the end where the spring is attached 15 thereto, as shown at 11, is to give sufficient depth at this point to accommodate both the spring and the head 14 of the riveting projection so that the

outer surface 15 of the projection will lie below the surface of the jack.

I claim:

A jack for use in knitting machines comprising a body portion having a shallow elongated recess in one side thereof, which recess is deeper at one end than the other, and a leaf spring in said recess, said body having integral therewith a spring-retaining projection extending from the bottom of the deeper portion of the recess through one end 10 of the spring, said projection having a greater transverse dimension in the lengthwise direction of the spring than in a direction transverse thereto and being headed over to retain the spring thereon, the exposed surface of the head lying below the side face of the jack. 15

EDMOND O. ROY.
